(57) **CLAIM**

The ornamental design for a standing support with integrated bench as shown and described.

DESCRIPTION

FIG. 1 is a front perspective view of a first embodiment of the standing support with integrated bench.

FIG. 2 is a front view of the standing support of FIG. 1.

FIG. 3 is a back view of the standing support of FIG. 1.

FIG. 4 is a left side view of the standing support of FIG. 1. FIG. 5 is a right side view of the standing support of FIG. 1.

FIG. 6 is a top view of the standing support of FIG. 1.

FIG. 7 is a bottom view of the standing support of FIG. 1.

FIG. 8 is a front perspective view of a second embodiment of the standing support with integrated bench.

FIG. 9 is a front view of the standing support of FIG. 8.

FIG. 10 is a back view of the standing support of FIG. 8.

FIG. 11 is a left side view of the standing support of FIG. 8. FIG. 12 is a right side view of the standing support of FIG. 8.

FIG. 13 is a top view of the standing support of FIG. 8; and, FIG. 14 is a bottom view of the standing support of FIG. 8. Surface texture presented in FIGS. 1-14 is intended to depict a wooden construction.

1 Claim, 8 Drawing Sheets
